UNITED STATES PATENT OFFICE

2,124,977

MULTISPEED ROLL FOR IRONERS

Joseph W. Jensen, Chicago, Ill., assignor to Electric Household Utilities Corporation, Chicago, Ill., a corporation of Illinois

Application November 13, 1936, Serial No. 110,561

14 Claims. (Cl. 38—65)

This invention relates to ironing machines of the type having a horizontally disposed, rotating roll and a cooperating shoe, and wherein the roll is supported and driven solely at one end thereof.

More specifically, the present invention contemplates the provision of a multi-speed drive for the ironer roll. It is recognized that some effort has been made to devise ironer constructions in a manner so that the roll proper may also be driven at a relatively low or slow speed, in addition to what has generally been found and considered a normal ironing speed. Such constructions as have been heretofore produced have necessitated complete re-design of the driving mechanism for the ironer roll and due to limitations of space and the desirability of compactness of construction, and general appearance, the multi-speed drive connection as heretofore embodied in such machines are usually such that the low or slow speed has invariably been found to be an impractical speed for ironing articles of wearing apparel, etc.

There are certain recognized advantages resulting from the embodiment of a drive mechanism which also permits rotating the ironing roll at a relatively slow practical ironing speed, as for example, it permits proper and convenient ironing of certain delicate or difficult articles of wearing apparel, etc. Another advantage is that it permits proper ironing of various articles that are relatively damp, such as articles which contain such an amount of moisture that it would ordinarily necessitate passing said article through the machine more than once, at the normal ironing speed, in order to substantially remove all the moisture from said article for preserving the effect of the ironing operation.

One of the primary objects of the present invention is to provide a novel multi-speed drive mechanism, for a rotating roll of an ironing machine, which is rugged in construction, positive in operation and capable of being economically manufactured.

Another object resides in the provision of a novel multi-speed drive mechanism constructed and arranged for adaptation to the free unsupported end of the roll.

A further object is to provide a novel multi-speed drive mechanism constructed and arranged for mounting in the free unsupported end of the roll without the necessity of disturbing or in any manner altering the conventional driving mechanism located at the supported end of the roll and which mechanism may be understood to be

of the type usually employed for rotating the roll at a single normal ironing speed.

Still another object is to provide an improved mechanism which provides a practical low or slow roll speed that permits proper ironing of certain delicate or difficult pieces of wearing apparel and permits a beginner to readily learn how to manipulate the ironer in ironing various articles.

Other objects and advantages of this invention will be apparent from the following description, taken in connection with the accompanying drawings, in which:

Fig. 1 is a fragmentary view of the unsupported end of the ironing roll, with portions broken away to show in section the multi-speed drive mechanism embodying the present invention.

Fig. 2 is a view similar to Fig. 1 showing the mechanism in another position of adjustment.

Fig. 3 is an enlarged transverse sectional view taken substantially as indicated at line 3—3 on Fig. 1.

Fig. 4 is a transverse sectional view through the splined connection of the drive mechanism, taken as indicated at line 4—4 on Fig. 1.

Fig. 5 is a diagrammatic elevational view of an ironing machine embodying the multi-speed drive mechanism constituting the present invention.

For purpose of illustration I have shown rather diagrammatically in Fig. 5 a conventional form of ironing machine including a motor A which is operatively connected to suitable drive mechanism enclosed in a housing B. A rotatable ironing roll, designated at 10, is wholly supported at one end by the housing B where it is operatively connected with the driving mechanism for actuation in a well-known manner. Associated with the roll 10 is a shoe indicated at C, which is adapted to be moved into and out of cooperating relation to the roll by suitable well-known mechanism which constitutes no part of the present invention, and therefore requires no illustration.

Said roll 10 includes a tubular body element 11, preferably of metal, the exterior surface of which is provided with one or more layers of suitable resilient material 12, encased in a suitable fabric covering 13. The extreme outer end of the body 11, is reinforced by an annular metal band 14, spot-welded or otherwise secured to the interior of the tubular body 11. It is to be understood that the ironer to which this invention is adaptable is of the type wherein the roll is supported at and driven solely from one end of the roll.

Extending longitudinally and axially of the roll 10 is a tubular sleeve 16, for supporting said roll body 11, and which may be understood to be mounted within the roll 10 in a manner somewhat similar to that embodied in single or multi-speed commercial forms of rotating roll type ironers. The end of said tubular sleeve 16 is supported concentrically within the tubular body 11, as will hereinafter be described. Disposed within the 10 tubular sleeve 16 is a driving shaft 17 which is connected to suitable means for imparting rotation to the roll 10. It is to be understood that the opposite end of said shaft, (not shown) is connected to conventional driving mechanism which 15 is capable of manipulation under the control of the operator.

As may be seen in the drawings, the shaft 17 extends a short distance beyond the tubular sleeve 16, and rigidly secured to said extended portion 20 of the shaft by means of one or more set screws 19, is a drive element 20 whose exterior surface is provided with a plurality of splines 21. Journaled and axially movable on the outer end of the sleeve 16 is a housing 23 which is provided 25 with a hub portion 24, having a bushing 25 drive-fitted therein for bearing support upon the exterior of the sleeve 16. Said hub portion continues into an outward extension 26 the extreme 30 end of which is threaded and engaged by a closure element 27 which serves as a convenient knob for operating the multi-speed mechanism. The internal portion of said extension 26 is provided with splines 29 cooperating with splines 21 of the element 20. Positioned intermediate the 35 adjacent ends of the splined element 20 and the tubular sleeve 16 and circumscribing the driving shaft 17 is a washer 31 which serves as a stop for one shoulder of the internal splined portion 29, of the hub extension 26, and limits inward 40 movement of the housing 23, as seen in Fig. 1. The opposite shoulder of said splined portion 29 limits the outward movement of the housing 23 by contact with a cap plate 33 secured to the 45 end of the splined element 20 by screws 34, as seen in Fig. 2.

The inner end of the housing 23 terminates in an enlarged annular drum-like portion 23a in the end of which is press-fitted an annular clutch element 36 in the form of an internal gear ring, 50 adapted for selective engagement with a cooperating clutch element 37 secured by means of bolts 38 to a dished support 39 which is formed with an annular flange 39a, spot-welded or otherwise rigidly secured to the interior of the tubular body 11. The central portion of said member 39 is formed with an annular reversely extending flange 39b in which is press-fitted a bushing 40 adapted for journal support on the external surface of the tubular sleeve 16. The clutch element 37 may be of any desired form and, as herein shown, is in the form of a gear, adapted to mesh with the gear ring 36.

In the position of the parts shown in Fig. 1 the shaft 17 drives the splined element 20, which 65 in turn rotates the housing 23 through the splined connection of the hub extension 26, and because the clutch elements 36 and 37 are in operative engagement, motion is transmitted directly through the clutch element 37 to the support 39, directly rotating the roll 10. It is to be understood that this arrangement of the driving mechanism rotates the roll 10 at which is considered a normal operating speed.

For changing the speed of rotation of the roll 70 10 to low or slow speed, the knob member 27

is grasped and pulled outward to the position seen in Fig. 2, in which position the housing 23 has been moved so that the gear ring 36 is in mesh with a pinion 45 journaled on a stud 46 rigidly secured in a boss 37a of the clutch member 37. Said pinion 45, as may be seen in the drawings, is constantly in mesh with a planet gear 48 which is rigidly secured on the supporting tube 16 by one or more set screws 49, in its hub 48a. In this position of adjustment of the mechanism it will now be apparent that the pinion 45 which is connected to the clutch member 37 and which in turn drives the roll by virtue of its connection to the dished support 39, substantially reduces the speed of rotation of the roll 10.

It is to be understood that the end of the teeth of the pinion 45 adjacent the boss 37a and both ends of the teeth of the gear ring 36, as well as the outer ends of the teeth of the gear ring 37, are beveled so that upon longitudinal movement 20 of the housing 23, the gear ring 36 may quickly and easily mesh with either the teeth of the clutch member 37 or the teeth of the pinion 45. By virtue of this construction it is possible to change the speed of the roll while it is operating. 25

As above mentioned, the washer 31 serves as a stop adapted to be engaged by the shoulder of the splined portion 29 of the hub extension 26 when said housing is moved inwardly to the position seen in Fig. 1, while the shoulder formed at the 30 opposite end of the splined portion 29 is adapted to abut against the cap plate 33 when the housing 23 is withdrawn to the position seen in Fig. 2 which corresponds to the low driving speed for the roll 10.

Although I have shown and described a preferred embodiment of my invention, manifestly it is capable of modification and variation without departing from the spirit and scope thereof. I do not, therefore, wish to be understood as 40 limiting this invention to the precise construction herein disclosed, except as it may be so limited in the appended claims.

I claim:

1. In an ironing machine, in combination, a 45 rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in said roll and having connection to said shaft for driving said roll at a plurality of different speeds.

2. In an ironing machine, in combination, a 50 rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means 55 mounted in said roll and having connection to said shaft for driving said roll at a plurality of different speeds, said selectively adjustable means including a plurality of separate positive driving connections from said shaft to said roll.

3. In an ironing machine, in combination, a 60 rotatable roll having support means and driving mechanism at one end of the roll, a stationary tubular roll supporting element disposed substantially centrally in said roll and carried by the support means, a shaft disposed within the tubular element and connected to said driving mecha- 65

- 10 4. In an ironing machine, in combination, a rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in said roll and having connection to said shaft for driving said roll at a plurality of different speeds, said selectively adjustable means including a plurality of axially spaced drive connections from said shaft to the roll, an axially movable control member for selectively engaging any of said drive connections for rotating said roll at one of said speeds, and stop means for positioning cooperating members at any of said drive connections.
- 15 5. In an ironing machine, in combination, a rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in said roll and having connection to said shaft for driving said roll at a plurality of different speeds, said selectively adjustable means including a plurality of axially spaced drive connections from said shaft to the roll, and an axially movable control member for selectively engaging one of said drive connections from said shaft to the roll, and a support rigidly attached thereto and to the roll for driving said roll.
- 20 6. In an ironing machine, in combination, a rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in said roll and having connection to said shaft for driving said roll at a plurality of different speeds, said selectively adjustable means including a plurality of axially spaced drive connections from said shaft to the roll, and an axially movable control member for selectively engaging any of said drive connections for rotating said roll at one of said speeds, and stop means for positioning cooperative members at any of said drive connections.
- 25 7. In an ironing machine, in combination, a rotatable roll having support means and driving mechanism at one end of the roll, selectively adjustable means carried in said roll for driving it at different speeds, and means for connecting said selectively adjusting means and said driving mechanism.
8. In an ironing machine, in combination, a rotatable roll having support means and driving mechanism at one end of the roll, a stationary roll supporting element disposed in said roll and carried by the support means, a shaft extending through said roll and connected to said driving mechanism, and adjustable means mounted in said roll and having connection to said shaft for selectively driving said roll at different speeds.
- 30 9. In an ironing machine, in combination, a rotatable roll having support means and driving mechanism at one end of the roll, a stationary tubular roll supporting element disposed substantially centrally in said roll and carried by the support means, a shaft extending through said roll and connected to said driving mechanism, and adjustable means mounted in said roll and having connection to said shaft for selectively driving said roll at different speeds, said selectively adjustable means including a plurality of separate positive driving connections from the free end of said shaft to said roll.
- 35 10. In an ironing machine, in combination, a rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in the end of said roll opposite the support and having connection to said shaft for driving said roll at a plurality of different speeds, said selectively adjustable means including a plurality of axially spaced drive connections from said shaft to the roll, and an axially movable control member for selectively engaging one of said drive connections for rotating said roll at one of said speeds.
- 40 11. In an ironing machine, in combination, a rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in the end of said roll opposite the support and having connection to said shaft for driving said roll at a plurality of different speeds, said selectively adjustable means including a plurality of axially spaced drive connections from said shaft to the roll, an axially movable control member for selectively engaging any of said drive connections for rotating said roll at one of said speeds and stop means for positioning cooperative members at any of said drive connections.
- 45 12. In an ironing machine, in combination, a rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in the end of said roll opposite the support and having connection to said shaft for driving said roll at a plurality of different speeds, said selectively adjustable means including a plurality of axially spaced drive connections from said shaft to the roll, and an axially movable control member for selectively engaging one of said drive connections for rotating said roll at one of said speeds, one of

said drive connections comprising a clutch member and a support rigidly attached thereto and to the roll for driving said roll.

13. In an ironing machine, in combination, a rotatable roll having support means and driving mechanism at one end of the roll, a stationary tubular roll supporting element disposed substantially centrally in said roll and carried by the support means, a shaft disposed within the tubular element and connected to said driving mechanism, and selectively adjustable means mounted in the end of said roll opposite the support and having connection to said shaft for driving said roll at a plurality of different speeds, said selectively adjustable means including a plurality of axially spaced drive connections from said shaft to the roll, and an axially movable control member for selectively engaging one of said drive connections for rotating said roll at one of said speeds, one of said drive connections comprising a clutch member and a support rigidly attached thereto and to the roll for driving said roll at the same speed as said shaft, and another of said drive connections including a gear reduction for rotating said clutch and support member together with said roll at a lower rate of speed.
14. In an ironing machine, in combination, a rotatable roll having support means and driving mechanism at one end of the roll, a stationary tubular roll supporting element disposed substan-
